LOUVER WINDOW
Earl D. Wilcox, 760 W. 190th St., Gardena, Calif.
Filed May 10, 1963, Ser. No. 279,478
3 Claims. (Cl. 189—62)

The present invention relates to louver window construction and specifically to the means for controlling the opening and closing thereof.

The average louvered window construction consists of a multiple number of window panes, each held by suitable end framing with means for turning the end framing to move the panes in position of overlap or separation. The window panes are of the same size and generally the construction is such as to maintain the window panes horizontally, although often times vertical panes are used. Such a construction, due to the number of window panes, is usually heavy and as a result the means for operating the louvered windows is complicated, and likewise expensive to construct.

An object of my invention is to provide a louvered window construction which may utilize both for the window pane holder, as well as the operating means therefor, light weight metal stampings with resulting saving in the cost of manufacture.

A further object is the provision of louver window construction wherein the operating mechanism is concealed from view, thus improving appearance.

A further object is the provision of a louvered window construction so formed that individual panes of glass may be readily removed or inserted within the glass holders without the necessity of dismantling the louvered window construction.

A further object is to provide a novel construction from light weight, soft aluminum stampings for individual actuator arms and glass holders and in such a manner that the two parts are held together for maximum shear strength and torque resistance.

My louver window construction employs side jambs which enclose the operating mechanism for the window louvers. The construction is such that glass holders for ends of the glass panes or panels and the actuator means therefor have bearing engagement with a window jamb. The construction results in one that holds the window panels firmly and allows easy movement of the operating mechanism for turning the window panels without distortion or twist.

My operator assembly assumes perfect balance of the panes during opening and closing thereof even during adverse weather conditions.

Other objects include a louvered window construction of few parts, easily assembled and generally superior to louver window constructions now known to the inventor.

With the above mentioned, and other objects in view, the invention consists in the novel and useful provision, formation, construction, association and relative arrangement of parts, members, and features, all as shown in one embodiment in the accompanying drawings, described generally and more particularly pointed out in the claims.

In the drawing:

FIGURE 1 is a fragmentary front elevation showing several window panels incorporating the construction of the present invention;

FIGURE 2 is a fragmentary, partially sectional view, on an enlarged scale, taken on the line 2—2 of FIGURE 1;

FIGURE 3 is a fragmentary elevation, on an enlarged scale, taken on the line 3—3 of FIGURE 1;

FIGURE 4 is a view similar to that of FIGURE 3, certain parts being in moved position;

FIGURE 5 is a fragmentary sectional view, on an enlarged scale, on the line 5—5 of FIGURE 3;

2

FIGURE 6 is a side elevation, partly in fragment and in section, of a glass holder of the invention; and,

FIGURE 7 is a plan view of the actuator arm for the glass holder of FIGURE 6.

I have shown in FIGURE 1, in fragment, several panes or panels of glass 1, in overlapped position. These panes or panels are adapted to be carried at the ends of each pane or panel, and particularly at the operating ends thereof in glass holders, designated generally as 2. The glass holders are ordinarily known as clips. Each holder 2 is of channel form having a web or base 3 and two flanges 4 and 5. The flanges are substantially of the same length although offset so that the end of flange 5, as shown at 6, extends beyond the end of flange 4, as indicated at 7. The opposite end 8 of flange 4 extends beyond the end 9 of flange 3. The end portion 7 of flange 4 is bent at a slight angle toward flange 5 and the opposite end of flange 4 at 8 has a tab 10 at substantially right angular relationship to the flange 4. The end 6 of flange 5 is bent inwardly at an obtuse angle as shown at 11. In forming the glass holder, the flange 5 is interrupted to provide a boss 12 which lies in the plane of the web 3. As shown in FIGURE 6, a semi-circular portion to complete the boss lies beyond the web. The boss on its external surface which is the surface shown in FIGURE 6, is raised above the plane of the web 3 and provided with a series of spaced apart parallel embossed ribs 13 and, likewise, provided at 14 with an annular bearing rib surrounding the raised boss. The boss is formed with a central hole at 15. Thus, as shown in FIGURE 2, one end of a glass pane is received within the glass holder or clip between the flanges, the upturned portion 11 and the tab 10 limiting end movement of the glass pane while the inwardly bent portions at 7 and 9 bear against opposite sides of the pane to firmly hold the glass pane in the holder.

The actuating arm 20 has two portions 21 and 22 in offset parallel relationship through the medium of an offset interconnecting wall 23. Portion 21 is provided with an extruded boss 24 and portion 22 is provided with embossed parallel ribs 25 which are adapted to interlock with the ribs 13 of boss 12. Portion 22 is provided with a central opening at 26. Portion 21 of the arm 20 may be stiffened by depressing the same, as shown at 27.

The actuator end of each pane or panel is supported by a jamb 30 of channel form. The jamb has a web 31, a pair of parallel flanges 32 and 33 which terminate in flanges 34 and 35, the latter flanges lying in the same plane, as shown in FIGURE 5. Flanges 34 and 35 are spacedly provided with holes whereby the jamb may be secured within a window framing by means of screws passed through said holes. Depending upon the width of each panel or pane, so that the panes may overlap in closed position, as shown in FIGURE 1, the web of the jamb is provided with spaced holes 36. In this connection it is to be observed from FIGURE 5 that the web is provided with an elongated channel type rib 37 intermediate the flanges 32 and 33 which intermediate rib secures in the channel thereof a weatherstrip 38 which bears against the base of a holder 2, to provide a weather seal for the pane.

The raised boss 12 of a window holder 2 is passed through a hole 36 in the jamb 30 and an actuating arm is positioned within the jamb with the ribs 25 thereof interlocking with the ribs 13 of the boss 12, the boss 12 and actuating arm being secured together by a rivet or equivalent means 39. This positions the web of the jamb between the actuating arm portion 22 and the boss 12 of the window holder. It is noted that the diameters of the boss 12 and part 22 are greater than the diameter of hole 36 and that the annular rib 14 has bearing engagement with the web of the jamb. An operating bar 40

is within that portion defined by the rib 37 and the flange 32, and the operating bar is provided with spaced holes 41, the holes of which receive bosses 24 of the actuating arms 20. Each boss 24 is held within a bore 41 of the operating bar when the ribs of the boss 12 and the ribs 25 of portion 22 of an actuating arm is held in cooperative relationship by the rivet 39.

The flange 33 may be stamped so as to provide an elongated slot at 50 defined by two internal separated and parallel internal elongated flanges 51 and 52. An operating lever 55 extends inwardly of the jamb 30 between the flanges 51 and 52 and is intermediately pivotally secured to a link 56 which link depends from and is riveted at 57 to both the web of the jamb and to a lug 58. Lug 58 is fastened in any suitable manner to flange 33. End 59 of the lever 55 is pinned at 60 to the operating bar 40. A toggle arrangement is thereby provided in that when the outer end of the lever 55 is moved downwardly to the dotted line position 61 in FIGURE 3, the panes are in open position and when the lever is moved from the position shown at 61 to that of 62 in FIGURE 3, the panes are locked in overlapped position, the locking resulting from the toggle arrangement shown in FIGURE 3 by full lines.

The operation, uses and advantages of my invention are as follows.

The non-operator end of each pane or panel may have its glass holder held by a rivet and washer of sufficient size and shape to provide a bearing surface on the jamb.

I have found that my construction operates easily and smoothly, is wear resistant, with no parts subject to breakage. Tests that I have run on the actuating arm and boss construction for the glass holder have shown that when the boss and end 22 of the actuating arm are secured together, that the parts will not separate, but will resist all stress to the end that positive movement of the glass holders always results when the actuating arms are moved by the operating bar 40. This has been one of the difficulties which I have overcome by my actuator construction, as I may employ a light weight, soft metal such as aluminum, or an aluminum alloy and secure the glass holder and actuating arm together in positive stress resisting working relationship. Prior manufacturers have had difficulty effecting a joinder of the actuating arms with the glass holders and have resorted to various expensive constructions to effect such a connection. It is also evident that when the glass holders are moved over the weatherstrip 38 that there is considerable drag which directly effects any connection which may exist between an actuating arm and a glass holder. Such a drag has no effect on my construction.

I have previously pointed out that glass panels may be easily received within the glass holders or removable therefrom due to the resilient end.

To install my actuator assembly the link 56 is riveted

to the operating lever 55 and the lever is riveted or pinned at 60 to the operating bar 40. This operation is performed outside of the jamb. Thereafter the assembly aforesaid is placed within the jamb with the lever 55 passed through slot 50. The link 56, lug 58 and jamb web are riveted together by rivet 57. The actuator arms and glass holders are positioned relative to the jamb and riveted as shown at 39, with the boss 24 placed in the holes 41 of the operating bar 40. By forming the actuating arm with the boss 24 for reception in a hole 41 of the operating bar, a riveting operation is not necessary resulting in easy parts assembly with resultant saving of time and expense.

In practice I have found it expedient to cant the ends 7 and 9 so that pane engagement is along the outer edge thereof. This prevents pane chipping.

I claim:

1. In louver window construction, the combination with a pair of jambs adapted to be secured to a window framing, each jamb provided with aligned bearing openings, of: glass holders swingingly supported in each bearing opening of the jambs, the glass holders adapted to support between aligned pairs thereof a glass panel, each glass holder being of channel form and having a web 25 and a pair of flanges, the web of one of said glass holders provided with an extended half round portion extending beyond the flange and lying in the plane of the web, said extended portion and the web formed with a circular raised boss portion, the boss portion provided with a series 30 of spaced parallel ribs, said raised boss portion adapted to be received within a bearing opening of the jamb, and an actuator lever formed with ribs complementary to the ribs of the raised boss of the glass holder for engagement with the ribs of said boss, and a rivet securing the 35 ribs of the boss and actuator lever in working relationship.
2. The device as set forth in claim 1, each actuating lever formed with a tubular boss, there being an operating bar provided with holes for receiving each tubular 40 boss.
3. The device of claim 1: said web and said extended half round portion provided with an annular bearing rib surrounding the circular raised boss to provide a bearing 45 way for reception of the jamb portion surrounding a bearing opening.
